US00D333574S

United States Patent [19]

Ackeret

[11] Patent Number: Des. 333,574

[45] Date of Patent: ** Mar. 2, 1993

[54] PHOTO ORGANIZER

[75] Inventor: Peter Ackeret, Kusnacht, Switzerland

[73] Assignee: Showbox-System AG, Landquart, Switzerland

[**] Term: 14 Years

[21] Appl. No.: 599,346

[22] Filed: Oct. 17, 1990

[52] U.S. Cl. D6/300

[58] Field of Search D6/300-314; D11/131, 132, 133; 40/152, 152.1, 511, 513

[57] CLAIM

The ornamental design for a photo organizer, as shown and described.

DESCRIPTION

FIG. 1 is a front elevational view of a photo organizer showing a first embodiment of my new design;
 FIG. 2 is a left side elevational view thereof;
 FIG. 3 is a top plan view thereof;
 FIG. 4 is a rear elevational view thereof;
 FIG. 5 is a right side elevational view thereof;
 FIG. 6 is a bottom plan view thereof;
 FIG. 7 is a front elevational view of a photo organizer showing a second embodiment of my new design;
 FIG. 8 is a left side elevational view thereof;
 FIG. 9 is a top plan view thereof;
 FIG. 10 is a rear elevational view thereof;
 FIG. 11 is a right side elevational view thereof;
 FIG. 12 is a bottom plan view thereof;
 FIG. 13 is a front elevational view of a photo organizer showing a third embodiment of my new design;
 FIG. 14 is a left side elevational view thereof;
 FIG. 15 is a top plan view thereof;
 FIG. 16 is a rear elevational view thereof;
 FIG. 17 is a right side elevational view thereof;
 FIG. 18 is a bottom plan view thereof;
 FIG. 19 is a front elevational view of a photo organizer showing a fourth embodiment of my new design;
 FIG. 20 is a left side elevational view thereof;
 FIG. 21 is a top plan view thereof;
 FIG. 22 is a rear elevational view thereof;
 FIG. 23 is a right side elevational view thereof;
 FIG. 24 is a bottom plan view thereof;
 FIG. 25 is a front elevational view of a photo organizer showing a fifth embodiment of my new design;
 FIG. 26 is a left side elevational view thereof;
 FIG. 27 is a top plan view thereof;
 FIG. 28 is a rear elevational view thereof;
 FIG. 29 is a right side elevational view thereof;

FIG. 30 is a bottom plan view thereof;
FIG. 31 is a front elevational view of a photo organizer showing a sixth embodiment of my new design;
FIG. 32 is a left side elevational view thereof;
FIG. 33 is a top plan view thereof;
FIG. 34 is a rear elevational view thereof;
FIG. 35 is a right side elevational view thereof;
FIG. 36 is a bottom plan view thereof;
FIG. 37 is a front elevational view of a photo organizer showing a seventh embodiment of my new design;
FIG. 38 is a left side elevational view thereof;

FIG. 39 is a top plan view thereof;
FIG. 40 is a rear elevational view thereof;
FIG. 41 is a right side elevational view thereof;
FIG. 42 is a bottom plan view thereof;
FIG. 43 is a front elevational view of a photo organizer showing an eighth embodiment of my new design;
FIG. 44 is a left side elevational view thereof;
FIG. 45 is a top plan view thereof;
FIG. 46 is a rear elevational view thereof;
FIG. 47 is a right side elevational view thereof; and,
FIG. 48 is a bottom plan view thereof.
